PORTRABLE DOLL BED

Charles R. Pedro, Mina, Nev.

Filed June 3, 1965, Ser. No. 85,559

Term of patent 14 years

(Cl. D34—15)

Fig. 1

Fig. 3

The back of the doll bed is plain and unornamented.

The dotted lines showing the doll are for illustrative purposes only.

This application is a continuation-in-part of my U.S. design patent application, Serial Number D79-645, filed April 22, 1964 and now abandoned.

I claim:

The ornamental design for a portable doll bed, as shown and described.
